Primary Examiner — Jennifer L Watkins(74) *Attorney, Agent, or Firm* — Westman, Champlin & Koehler, P.A.; Z. Peter Sawicki; Amanda M. Prose**(57) CLAIM**

The ornamental design for an equestrian headpiece, as shown and described.

DESCRIPTION

The sole FIGURE is a perspective view of an equestrian headpiece.

The left and right sides of the headpiece are identical.

The top and bottom views of the headpiece are identical.

The front and back view of the headpiece are identical.

The broken lines in the drawings illustrate portions of the environmental structure that form no part of the claimed design.
